UNITED STATES PATENT OFFICE.

JAMES H. SAXE, OF MARKESAN, WISCONSIN.

BREAST-COLLAR.

1,099,823.

Specification of Letters Patent.

Patented June 9, 1914.

Application filed February 24, 1912. Serial No. 679,562.

To all whom it may concern:

Be it known that I, JAMES H. SAXE, a citizen of the United States, residing at Market-
5 san, in the county of Green Lake and State
of Wisconsin, have invented new and useful
Improvements in Breast-Collars, of which
the following is a specification.

The present invention relates to improvements in harness.

10 In carrying out my invention, it is my purpose to improve the construction of breast collars used in double harness, by rendering the same light, strong, and durable, and which at the same time will comfortably fit the horse wearing the collar and be free from projections or uneven surfaces which might rub or chafe the animal.

It is also my purpose to construct a collar for animals wherein the parts commonly 20 known as "breast collar irons" are dispensed with.

25 With the above and other objects in view, the invention resides in the construction, combination and arrangement of parts, set forth in and falling within the scope of the appended claim.

30 In the drawings: Figure 1 is a perspective view of the complete breast collar. Fig. 2 is a central vertical sectional view through the same.

Referring now to the drawings in detail, the numeral 1 designates the breast strap. This breast strap presents a perfectly flat smooth inner face, and the sides or exten- 35 sions of the said strap provide the integrally formed trace straps 2. The breast strap 1 has stitched thereto, upon its outer face, a binding or reinforcing strap 3, and connected with the said binding strap, at 40 the central portion of the breast strap, is a leather loop 4, through which passes the neck strap 5. The binding strap has its opposite ends formed with loops or eyes for the reception of the rings 6, and also connected with these rings 6 are the short brace straps 7. The free ends of the brace straps 7 are connected with metallic eyes 8, the said metallic eyes being secured between the binding strap and the breast strap by the

stitching which secures the binding strap to 50 the breast strap.

The numeral 9 designates the neck strap. This neck strap has its opposite ends slit- 55 ed to provide a front connecting strap 10, and a rear connecting strap 11. Both of these straps are provided with suitable buckles, and the rear connecting strap is at- 60 tached to the ring 6, while the front con- necting straps engage with metal loops 12 provided upon the front of the breast strap. 65 The loop 4, which is arranged at the central portion of the breast strap, extends below the binding strap 3, the said extending portion being provided with a metallic ring or loop 13. Connected with this loop 13 is a 70 short strap 14 which in turn is connected with the loop 15 provided upon the choke strap 16. The choke strap, above the ring 15, is provided with a suitable buckle, and the extremity of the said strap is formed 75 with a plurality of spaced perforations which are adapted to be received by the buckle and be engaged by the tongue of the buckle. This upper extension provides the auxiliary yoke strap 17 of the device. The 80 yoke strap proper which is designated by the numeral 18 passes over the breast strap and through the metallic ring 13. The said yoke strap 17 is provided with the usual buckle which is adapted to engage with the loop portion or extension of the said yoke strap 17.

From the above description, taken in connection with the accompanying drawings, it is thought that the operation, as well as 85 the advantages of the device will be perfectly apparent to those skilled in the art to which such inventions appertain, without further detailed description.

What is claimed is:

In a harness the combination of a breast strap, a neck strap, said neck strap having each end slit whereby two divided portions are formed, one of said divided portions being substantially shorter than the other, a 90 ring carried by said shorter portion, a lower U-shaped neck strap having its arms linked to the ring carried by said shorter portion,

said lower neck strap having its looped portion linked to the forward end of said breast strap, and brace straps linked to said rings and being secured obliquely with respect to 5 said U-shaped strap upon said breast strap and in diverging relation relatively to said U-shaped strap, the opposite divided portions continuing uninterruptedly to the

breast strap and secured thereto forwardly of the brace straps.

In testimony whereof I affix my signature in presence of two witnesses.

JAMES H. SAXE.
